HANGER

Michael Henry Kruger, Malden, Mass., assignor
to A. L. Smith Iron Company, Chelsea, Mass.,
a corporation of Massachusetts

Application October 4, 1946, Serial No. 701,137

10 Claims. (Cl. 248—343)

1

This invention relates to hangers for lighting fixtures in general and more especially to adjustable hangers.

Among the objects of the present invention it is aimed to provide an improved adjustable hanger which will adjust itself to accommodate irregularities and inclinations in ceilings to facilitate hanger stems in particular to extend vertically, and thus enable the hanger stems of several hangers of a group for a particular ceiling to be parallel and in alignment with one another, not only in the interest of appearance, but also in the interest of effectively distributing the light of a group of lighting fixtures for a given lighting effect or lighting efficiency.

It is still another object of the present invention to provide an improved hanger assembly, parts of which are convertible for use either with a plurality of hanger stems when spaced from an outlet box, or with a stud when disposed immediately adjacent the outlet box.

These and other features, capabilities and advantages of the present invention will appear from the subjoined detail description of one specific embodiment thereof illustrated in the accompanying drawings, in which

Fig. 1 is a side elevation partly broken away and partly in section showing the hanger in position ready to receive a lighting unit.

Fig. 2 is a perspective of a plate constituting one part of the hanger slightly enlarged as compared to Fig. 1.

Fig. 3 is a perspective of one of the smaller plates constituting another part of the hanger slightly enlarged as compared to Fig. 2.

Fig. 4 is a fragmental side elevation of the main plate and one of the smaller plates connected to a hanger stem.

Fig. 5 is a fragmental end elevation of the parts shown in Fig. 4.

Fig. 6 is a plan view of the small plate shown in Fig. 3 with a nut in position ready to receive a hanger stem.

Fig. 7 is a bottom plan view of a canopy construction adapted to cooperate with the improved hanger.

Fig. 8 is an enlarged fragmental section on the line 8—8 of Fig. 1 with a hanger stem anchored thereto.

Fig. 9 is a perspective partly exploded to illustrate the use of parts of the hanger assembly when secured adjacent of an outlet box instead of when spaced therefrom.

In the embodiment shown, there is provided a main plate 1 having longitudinally extending bent

flanges 2 and 3 in accordance with convention to receive a lighting unit, such as a fluorescent lighting unit, although obviously other fastening means could be provided for the supporting plate 1 of a lighting fixture without departing from the general spirit of the invention now to be described.

This plate 1 is provided with a plurality of H-shaped openings, two openings 4 and 5 being shown in the present instance. These openings each consists essentially of a wide opening 6 in communication at its lateral ends with the pairs of narrow longitudinally extending slots 7 and 8, the slots 7 being longer than the slots 8. Just beyond the outer ends of each pair of slots 7 and 8 and equally spaced from the ends of each pair of slots 7, there is provided a projection or pimple 9, and just beyond the outer ends of each pair of slots 8 and equally spaced from each pair of slots 8, there is provided a projection or pimple 10, the projections 9 and 10 being preferably in alignment with one another, as shown.

When only two H-shaped openings 4 and 5 are provided, then as an instance as shown the slots 7 may be located on the outer ends of the openings 4 and 5. The main plate 1 is preferably composed of sheet metal and when so constructed is preferably provided with a plurality of knockouts to facilitate using this plate for other purposes hereinafter to be described. In the present instance, this plate 1 is provided with a centrally disposed circular knockout 11 and two substantially rectangular knockouts 12 and 13 extending transversely of the plate 1, with the circular knockout 11 between the rectangular knockouts 12 and 13.

When the plate 1 is used with hanger stems and the plate 1 is spaced a substantial distance from the ceiling, then the assembly shown in Fig. 1 may be used to advantage. In this assembly there is shown a canopy 14 secured to the ceiling 15 in the conventional way adjacent to an outlet box, not shown. The canopy 14, in the present instance, is shown as composed of a sheet metal stamping having a plane plate area 16 surrounded by an expressed border 17 beyond which the surrounding plate portion 18 continues into the border flange 19, the free edge of which is shown as engaging the ceiling 15. The flange 19 may be provided with a plurality of knockouts, such as the knockout 20, one preferably being provided in each enlargement 21. The knockouts 20 are provided so that wires may be fed to the canopy 14 from an outlet box remote from the location of the canopy 14, when such wires may be housed

or enclosed in a molding attached to the ceiling in accordance with convention.

The plate portion 16, in the present instance, is provided with four openings 22, one adjacent each corner of the plate portion 16 to facilitate fastening the canopy 14 to the ceiling by means of screws or bolts when an outlet box fixture stud is not used. The plate portion 16 also is preferably provided with the centrally positioned enlarged depression 24 with an opening 25 in the center thereof. To either side of the depression 24, there is provided the enlarged opening 26 to afford access, as an instance, to the wires in the canopy 14. Furthermore, adjacent each end of the plate portion 16 there is provided the opening 27 having an inner enlarged portion 28 and an outer diminished portion 29. Extending upwardly from the enlarged opening portion 28, there is provided the flange 30, in full size approximately $\frac{1}{4}$ of an inch in altitude. Preferably in the interest of reenforcement, the plate portion 16 is also provided with transversely extending depressions, such as the two depressions 31, one intermediate each opening 26 and its adjacent enlarged opening portion 28. The plate portion is also provided with the U-shaped depressions 32 spaced from the edges of the diminished opening portions 29 and surrounding the outer ends thereof and terminating in the transversely extending depression portions 33. Preferably the plate portion 16 is also provided with two screw threaded openings 34, one disposed between each opening 26 and its adjacent depression 31 to receive screws 35 extending through openings formed in the cover plate 23. The cover plate 23 in outline conforms substantially to the plate portion 16 inside of the expressed border 17, with the exception of the V-shaped recesses 37, one at each end of the plate 23 to clear the diminished opening portions 29 for the purposes now to be described, when the plate 23 is secured to the canopy 14 by the screws 35.

This plate 23 is secured in position after the hanger stems 38 are secured in position. Each hanger stem 38 preferably is provided with an external thread 39 at its lower end to engage the nut 40 which is positioned on top of the plate 1 after being inserted in the openings 41 and 42 of the wings 43 and 44, respectively, of the small plate 45. The small plate 45, as shown in Figs. 3 and 6, preferably has a main plate portion 46 with an enlarged opening 47 in alinement with the openings 41 and 42. Preferably the plate 45 also has laterally extending from the plate portion 46, the wings 48, 49, 50 and 51. The small plate 45 when intended for anchoring a hanger stem 38 to the main plate 1 is initially secured in place by passing the wings 43 and 44 through the pairs of slot portions 7, 8 of an opening 4 or 5. If the small plate 45 is associated with the opening 4, then, see Fig. 1, the plate portion 46 is disposed below the main plate portion 1 and the wings 43 and 44 extend upwardly above the main plate portion 1. Thereupon a nut 40, see Fig. 6, is placed in position, it being initially inserted through the lateral extensions 52 and 53 of the openings 41 and 42, while pressing the plate 46 up into intimate engagement with the lower face of the main plate 1. After the nut 40 has been so inserted in the openings 41 and 42, the small plate 45 may then be released and it will remain anchored to the main plate 41, and the extensions 54 of the nut 40 will then be positioned in the diminished portions 55 of the openings 41 and 42. Preferably the upper edges 56 of the open-

ings 41 and 42 are convex to facilitate rocking of the nut 40 relative to the small plate 45. When the nut 40 is so positioned in the small plate 45, then the lower threaded portion 39 of the stem 38 is screw threadedly connected to the nut 40 and after the stem 38 has so been properly connected to the nut 40, then the upper head 57 of the stem 38 is initially passed through the enlarged opening 28 and then moved over into the diminished opening portion 29 where the head 57 rests on the free edge of the diminished opening portion 29, the neck 58 formed by the depressed sides 59 and 60 of the stem 38 being narrow enough to freely slide into the diminished opening portion 29, although the head 57 above the neck 58 is wider than the width of the diminished opening portion 29. The enlarged opening portion 28, however, is wide enough to allow the head 57 to pass up through the plate portion 16 and then enable the stem 38 to be moved over into the diminished opening portion 29 where the neck 58 registers with the edges of the diminished opening portion 29. The head 57 and neck 58 may be formed in any one of several well-known ways. However, excellent results have been achieved when the head 57 relative to the neck 58 is formed by merely depressing the two opposite faces of a tubular stem 38 into the form shown in Figs. 1 and 8. After the neck 58 has been so moved over into the diminished opening portion 29, then, when the plate 23 is secured in position by the screws 35 it will anchor the stem 38 in position.

Obviously when securing a lighting fixture in place, the plate 1 has one or more stems 38 secured to the same by nuts 40 and then the necks 58 of these stems 38 subsequently connected to the plate portion 16. When two stems 38 are relied upon for supporting the plate 1 of the lighting fixture, then the heads 57 of the two stems 38 may be anchored to the plate portion 16 by a plate, such as the plate 23 aforesaid.

As shown in Figs. 1 and 8, there is sufficient clearance between the neck 58 and the edges of the diminished opening portion 29 to enable the stem or stems 38 to swivel or move relative to the canopy 14, not only in a lateral direction, but also in a longitudinal direction.

Furthermore, when the plates 45 are positioned with their plate portions 46 engaging the lower faces of the plates 1, they, see Figs. 4 and 5, only engage the outer ends of the pimples or projections 9 and 10. Consequently the plate 1 may also rock relative to the stems 38. Consequently, since the diminished opening portions 29 of a canopy 14, when two are provided, are spaced from one another a distance corresponding to the distance that the enlarged portions of the openings 4 and 5 are spaced from one another, due to the freedom of movement provided by the present invention for the stems 38, the stems 38 may always assume a vertical position, although the canopy, due to irregularities or inclinations of the ceiling may not be perfectly horizontal. Obviously, however, the plate 1 if properly balanced, may with facility be positioned, when desired, to be truly horizontal by merely manipulating one or the other of the nuts 40 on the threads 39 on the stems 38 until the plate 1 is truly horizontal.

In some instances, the small plates 45 may also be provided with pimples, such as the pimple or projection 61, extending from the inner face of one or both of the wings 43, 44, one such pimple 61 projecting from the inner face of the

wing 43. The small plates 45 are preferably also composed of sheet metal stampings, and consequently there will be sufficient resiliency in the wings 43 and 44 so that when the wings 43, 44 of the plate 45 are pressed into a pair of openings 7, 8 of the plate 1, the projection 61 of wing 43 will yield when passing the lip 62.

The main plate 1 and smaller plates 45 cooperate in another respect. If the main plate 1 is not used with hanger stems, such as the hanger stems 38, and instead thereof is intended for use adjacent to a ceiling next to an outlet box, then the openings 4 and 5 would not be used for the hanger stems, but instead thereof the knockout 11 will be removed and a small stud or bushing, such as the bushing 63, may first be passed through the opening formed by removing the knockout 11 and then a nut 64 secured to the lower end thereof adjacent the lower face of the plate 1 and then the upper end of the bushing 63 connected to a connection in the outlet box or vice versa. When the plate 1 is so positioned adjacent the ceiling 15, then also the knockout 12 may be removed to form the opening 65 and enable the wires from the outlet box to pass therethrough to the lighting unit attached to, or parts of, the flanges 2 and 3.

Since the underwriters frequently require that a plate, such as the plate 1, adjacent the ceiling have as few openings therein as possible, the openings 4 and 5 could then be closed by the small plates 45. In this case, however, the plates 45 would have the plate areas 46 rest on the upper face of the plate 1, with the wings 43 and 44 inserted or extending down through the pairs of recesses 1 and 8. Furthermore, the openings 47 of the plates 45 would then register with the lips 62 so that the plate areas 46 of the plates 45 would cover the openings 4 and 5, see Fig. 9.

It is obvious that various changes and modifications may be made to the details of construction without departing from the general spirit of the invention as set forth in the appended claims.

I claim:

1. In a hanger for a lighting fixture, the combination of a bracket attached to a ceiling, hanger stems pivotally connected at their upper ends to said bracket, a main plate having openings therein, a plurality of small plates having main openings therein registering with the openings in said main plate and pivotally positioned adjacent the lower face of said main plate, said small plates having wings extending upwardly through the openings in said main plate, said small plates having openings in said wings, and nuts positioned in the wings of said small plates and registering with the main openings in said small plates, said stems having external screw threads adjacent their lower ends to receive said nuts, the nuts movably anchoring said stems to said wings in turn to support said main plate.

2. In a hanger for a lighting fixture, the combination of a bracket attached to a ceiling, hanger stems pivotally connected at their upper ends to said bracket, a main plate having openings therein, a plurality of small plates each having an intervening web and wings extending away from said web, there being openings in said intervening web registering with the openings in said main plate, projections on the lower face of said main plate engaging the intervening web of each small plate with the wings extending through the openings in said main plate to enable each

small plate to rock relative to said main plate, there being a pair of openings in the wings of each small plate in registration with one another, and a nut positioned in each pair of openings in the wings of a small plate, the stems extending into the openings in the intervening webs of said small plates and into the openings in the main plate in registration therewith and screw threadedly connected to said nuts.

3. The combination with the hanger of a lighting fixture having movably suspended hanger stems with external screw threads adjacent the lower ends of said stems, of a main plate having a plurality of openings with parallel narrow slots in communication with each of said openings, small plates each having an intervening web with an opening therein in registration with one of the openings in said main plate and a pair of wings extending through the narrow slots in said main plate, each pair of wings having openings in registration with one another, and a nut screw threadedly connected to the screw threads of a stem and positioned in the openings of a pair of wings with the stem extending into the opening in an intervening web and the opening in the main plate in registration therewith.

4. The combination with the hanger of a lighting fixture having movably suspended hanger stems with external screw threads adjacent the lower ends of said stems, of a main plate having a plurality of openings with parallel narrow slots in communication with each of said openings, small plates each having an intervening web with an opening therein in registration with one of the openings in said main plate and a pair of wings extending through the narrow slots in said main plate, each pair of wings having openings in registration with one another, a nut screw threadedly connected to the screw threads of a stem and positioned in the openings of a pair of wings with the stem extending into the opening in an intervening web and the opening in the main plate in registration therewith, and a projection in at least one of the wings of each small plate to cooperate with said main plate to anchor a small plate to said main plate.

5. The combination with the hanger of a lighting fixture having movably suspended hanger stems with external screw threads adjacent the lower ends of said stems, of a main plate having a plurality of openings with parallel narrow slots in communication with each of said openings, small plates each having an intervening web with an opening therein in registration with one of the openings in said main plate and a pair of wings extending through the narrow slots in said main plate, each pair of wings having openings in registration with one another, and a nut screw threadedly connected to the screw threads of a stem and positioned in the openings of a pair of wings with the stem extending into the opening in an intervening web and the opening in the main plate in registration therewith, each opening in a wing including a narrow portion and a large portion, the large portion enabling the nut to be inserted into place in the openings of the wings, and the narrow portion cooperating with the nut to anchor the same against movement.

6. The combination with the hanger of a lighting fixture having movably suspended hanger stems with external screw threads adjacent the lower ends of said stems, of a main plate having a plurality of openings with parallel narrow slots in communication with each of said

openings, small plates each having an intervening web with an opening therein in registration with one of the openings in said main plate and a pair of wings extending through the narrow slots in said main plate, each pair of wings having openings in registration with one another, and a nut screw threadedly connected to the screw threads of a stem and positioned in the openings of a pair of wings with the stem extending into the opening in an intervening web and the opening in the main plate in registration therewith, each opening in a wing including a narrow portion and a large portion, the large portion enabling the nut to be inserted into place in the openings of the wings, and the narrow portion cooperating with the nut to anchor the same against movement, the intervening web of each small plate engaging the lower face of said main plate and said narrow opening portion being disposed above the large opening portion so that the weight of the main plate when supported by said nuts will cause the nuts to be positioned in said narrow opening portions.

7. The combination of a plate of a hanger for a lighting fixture, said main plate having a plurality of openings with pairs of slots in communication with each of said openings, small plates each having an intervening web with an opening at one end and wings extending therefrom to enter a pair of slots, said slots and wings of each small plate being positioned relative to one another to have part of said intervening web cover an adjacent opening in said main plate in one position and in another position to have the opening in said small plate to register with one of the said openings in said main plate.

8. A hanger attachment for lighting fixtures including a canopy, means for fastening the canopy to a ceiling, said canopy having one set of openings to afford access to the wiring, and a second set of openings, each opening of said second set having an enlarged portion and a smaller portion, an upwardly extending flange surrounding the enlarged portion, a tubular rod for each opening of the second set and having parallel indentations adjacent the upper end thereof, the larger portion of each of said second set of openings enabling the said tubular rods to pass therethrough from below after installation, the smaller portion of each opening of said second set of openings corresponding to the width of the tubular rods at the indentations to receive the indented portions of the rods and anchor the rods in suspended position when the rods had been moved from the larger portions to the smaller portions of the openings of the second set, and a lighting fixture unit connected to the lower ends of said tubular rods.

9. A hanger attachment for lighting fixtures including a canopy, means for fastening the canopy to a ceiling, said canopy having one set of openings to afford access to the wiring and a second set of openings, each opening of said second set having an enlarged portion and a smaller portion, an upwardly extending flange surrounding the enlarged portion, a tubular rod for each opening of the second set and having parallel indentations adjacent the upper end thereof, the larger portion of each of said second set of openings enabling the said tubular rods to pass therethrough from below after installation, the smaller portion of each opening of said second set of openings corresponding to the width of the tubular rods at the indentations to receive the indented portions of the rods and anchor the rods in suspended position when the rods had been moved from the larger portions to the smaller portions of the openings of the second set, an anchoring plate having openings registering with said tubular rods when registering with the smaller portions of the openings of said second set to anchor said tubular rods in position relative to said canopy, and a lighting fixture unit connected to the lower ends of said tubular rods.

10. A hanger attachment for lighting fixtures including a canopy, means for fastening the canopy to a ceiling, said canopy having one set of openings to afford access to the wiring and a second set of openings, each opening of said second set having an enlarged portion and a smaller portion, an upwardly extending flange surrounding the enlarged portion, a tubular rod for each opening of the second set and having diminished portions spaced from their upper free ends, the larger portion of each of said second set of openings enabling the said tubular rods to pass therethrough from below after installation, the smaller portion of each opening of said second set of openings corresponding to the width of the tubular rods at their diminished portions to receive the diminished portions of the rods and anchor the rods in suspended position when the rods had been moved from the larger portions to the smaller portions of the openings of the second set, and a lighting fixture unit connected to the lower ends of said tubular rods.
